UNITED STATES PATENT OFFICE.

HAROLD E. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

CIRCULAR-KNITTING MACHINE.

1,204,444.

Specification of Letters Patent. Patented Nov. 14, 1916.

Application filed June 16, 1916. Serial No. 103,913.

To all whom it may concern:

Be it known that I, HAROLD E. HOUSEMAN, a citizen of the United States, residing at Philadelphia, county of Philadelphia, and 5 State of Pennsylvania, have invented a new and useful Improvement in Circular-Knitting Machines, of which the following is a full, clear, and exact description, reference being had to the accompanying drawings, 10 which form a part of this specification.

Needles employed in circular knitting machines are vertically slidable in slots or grooves cut in the needle cylinder. The needles are made of a thickness slightly less 15 than the width of the grooves, so that, if the needles were perfectly straight, they would slide therein freely. However, in the knitting operation, the needles are moved up and down by means of cams and, on the 20 revoluble needle cylinder type of machine, by pickers, and it is necessary that the needles shall remain at the level to which they are raised when they pass beyond the influence of the devices which so raise them. 25 Accordingly, it is customary to bend the needles somewhat so that, when inserted in the needle cylinder slots, they shall bear with some degree of friction against the walls thereof. The degree of frictional engagement must be sufficient to insure the needles remaining at any level without liability 30 to drop by gravity aided by the jars and vibrations to which such machines are inevitably subject, but at the same time the frictional engagement must not be so great as to impose too much strain upon the cams. This bending operation is applied to the needles by the manufacturers, and inasmuch as each needle must be carefully and skilfully bent 35 separately, and inasmuch as several hundred needles are required to equip a single cylinder, it is obvious that the operation involves a serious addition to the cost of manufacture. Unfortunately, however, the variation 40 in the temper of different needles is so great that the mill operator finds it necessary, before applying the needles to the cylinder, to carefully test the individual needles and rebend them more or less so that 45 they will have the required uniform and approximately exact degree of frictional contact with the walls of their slots that is necessary to produce smooth and satisfactory operation. This work still further adds to 50 the equipment cost. Notwithstanding this

careful and tedious work, it is found practically impossible to attain any fair approximation to ideal results. If the needles engage the walls of their grooves with too great a degree of friction they impose so 60 great a strain upon the cams that the latter speedily wear out; whereas if the needles slip too freely in their grooves, they eventually slide up and down so loosely that sooner or later they drop in their slots during the 65 operation of the machine, and striking the solid face of a cam, are broken, with resultant danger of injury to other needles and the delicate mechanism for actuating them, as well as the loss of time and production involved in the work of replacement and repair. 70

The object of my invention is to dispense with the necessity of hand-bending the needles, thereby greatly simplifying and cheapening both their manufacture and their application to the needle cylinder. 75

A further object of the invention is to provide means whereby the frictional engagement of the needles with the walls of their slots may be effected after the needles have been applied to the cylinder. 80

A further object of the invention is to provide means whereby such frictional engagement may be accurately adjusted and 85 regulated.

Another object of the invention is to apply this adjustable friction to all the needles simultaneously and by a single simple operation. 90

Another object of the invention is to provide means whereby the degree of this frictional engagement will not tend to diminish after a few days' running of the machine.

Having now set forth the objects of my invention and the principal advantages to be derived therefrom, I will proceed to describe in detail a needle cylinder of a circular knitting machine embodying my invention, in connection with the accompanying drawings, in which— 95

Figure 1 is an elevational view, principally in central section, of a needle cylinder with my invention applied thereto. Fig. 2 is a partial horizontal section through same. Fig. 3 is an enlarged explanatory view, showing the action of my invention upon the needles. 105

The needle cylinder *a* has the usual radial slots or grooves *b* in which slide the needles 110

5 *c*, actuated by cams mounted on the stationary cam ring *d*. The sinker head *e* is attached to rotate with the needle cylinder as usual, the sinker cams being located in the stationary top plate *f*, which is held from rotation in the usual manner (not shown).

10 Surrounding the cylinder just below the sinker head *e* is loosely mounted a circular plate *g* having radial grooves cut in its under face for the fingers *h*. These fingers fit tightly enough in said slots to remain in any position in which they are placed. A groove *i* is cut in the outer wall of the cylinder, deeper than slots *b*, and into which 15 the ends of the fingers project without touching. The ends of fingers *h* enter between the needles, similarly to the sinkers, and they are equally spaced, and equal in number to the needles.

20 Below plate *g* and fingers *h* a disk *j* surrounds the cylinder and is attached thereto. This is for the purpose of supporting the loosely mounted plate *g*. A lug *k* projects from the hub of sinker head *e*, and there is 25 a projection *l* upon plate *g*, circumferentially in line with lug *k*. A set screw is threaded through projection *l* and abuts against lug *k*, in such manner that by screwing the set screw plate *g* may be turned relatively to the needle cylinder. This turning will bring the fingers *h* against one side of the needles *e*, and a further turn of the set screw will bring a certain side pressure to bear upon each needle by its corresponding 30 finger. This presses the needles to one side of their slots, and gives them a certain bend as indicated in Fig. 3. The degree of this side pressure upon the needles may be nicely determined and adjusted by set screw *m*; and 35 the needles thereby given the amount of bend necessary to hold them in their slots with the required amount of friction. In this way perfectly straight needles are used in the machine. This means cheaper needles, 40 for they will not have to go through the final bending operation, as heretofore, by the manufacturer and operator.

45 Instead of having needles of various degrees of frictional contact, due to the individual bending of each needle separately, the turning of plate *g* presses the end of the finger *h* against the needles *e* with an equal and uniform pressure, which may be made greater or less, as desired. Thus plate 50 *g*, while loose upon the cylinder, is confined between lug *k* and set screw *m* on the one side and the contact of the fingers on the needles on the other side, and held as rigidly in the position set as if it were attached to 55 the cylinder.

60 Having now fully described my invention, what I claim and desire to protect by Letters Patent is:

65 1. In a circular knitting machine, in combination, a needle cylinder provided with

grooves in which the needles are adapted to slide vertically, and devices adapted to extend between the needles between the upper and lower ends of their supporting grooves and by sidewise engagement with the needles hold them from dropping in their grooves. 70

2. In a circular knitting machine, in combination, a needle cylinder provided with grooves in which the needles are adapted to slide vertically, devices adapted to engage the respective needles between the upper and lower ends of their supporting grooves, and means common to all of said devices to simultaneously vary the degree of frictional pressure imposed upon the 80 needles. 75

3. In a circular knitting machine, in combination, a needle cylinder provided with grooves in which needles are adapted to slide vertically, fingers adapted to project 85 between adjacent needles and engage the respective needles between the upper and lower ends of their supporting grooves and normally maintain them in frictional contact with the walls of their grooves, and 90 means common to all the fingers to manipulate them to regulate the degree of said frictional contact.

4. In a circular knitting machine, in combination, a needle cylinder provided with 95 grooves in which the needles are adapted to slide vertically, means carried by the needle cylinder adapted to engage the respective needles and frictionally hold them from dropping in their grooves, and manually adjustable mechanism to hold said means with a regulatable degree of pressure against the needles in fixed relation to the needle cylinder 100 during the operation of the machine.

5. In a circular knitting machine, in combination, a needle cylinder provided with grooves in which the needles are adapted to slide vertically, an integral ring surrounding the needle cylinder, devices carried thereby adapted to engage the respective needles throughout the entire circumference of the needle cylinder, and manually adjustable means to hold said devices with a regulatable degree of pressure against the needles 110 in fixed relation to the needle cylinder during the operation of the machine. 115

6. In a circular knitting machine, in combination, a needle cylinder provided with grooves in which the needles are adapted to slide vertically, the walls of the grooves being cut away to form a continuous open space of limited height extending circumferentially around the cylinder, and radially extending fingers supported from the needle cylinder and extending into said open space 120 between needles and adapted to frictionally engage the needles to hold them from dropping in their grooves. 125

7. In a circular knitting machine, in combination, a needle cylinder provided with 130

- grooves in which the needles are adapted to slide vertically, the walls of the grooves being cut away to form a continuous open space of limited height extending circumferentially around the cylinder, a ring surrounding the needle cylinder, radially extending fingers carried by the ring and extending into said open space, and members, one carried by the ring and the other by the needle cylinder arranged to abut one against the other and thereby hold the fingers pressed against the needles.
8. In a circular knitting machine, in combination, a needle cylinder provided with grooves in which the needles are adapted to slide vertically, the walls of the grooves being cut away to form a continuous open space of limited height extending circumferentially around the cylinder, a ring surrounding the needle cylinder, radially extending fingers carried by the ring and extending into said open space, and means to turn and hold said ring in position to cause the fingers carried thereby to press said needles against the walls of their grooves.
9. In a circular knitting machine, in combination, a needle cylinder provided with grooves in which the needles are adapted to slide vertically, the walls of the grooves being cut away to form a continuous open space of limited height extending circumferentially around the cylinder, an annular member surrounding the needle cylinder and fixed relatively thereto, a ring also surrounding the needle cylinder, radially extending fingers carried by the ring and adapted to extend into said open space between needles, and means to adjust the ring circumferentially relative to said annular member, thereby causing said fingers to engage the respective needles and press them against the walls of the grooves to regulate the degree of frictional engagement between the needles and the needle cylinder.
10. In a circular knitting machine, in combination, a needle cylinder provided with grooves in which needles are adapted to slide vertically, the walls of the grooves being cut away to form a continuous open space of limited height extending circumferentially around the cylinder, a sinker head and a ring surrounding the needle cylinder and fixed relatively thereto and spaced apart, a ring surrounding the needle cylinder and located between the sinker head and the fixed ring and supported by the latter, the second ring being slotted in a radial direction, radially extending fingers in the slots of the second ring extending into said open space between adjacent needles, a lug on the sinker head, a lug on the second ring, and a screw thread in one lug and engaging the other lug whereby the second ring may be adjusted circumferentially relatively to the sinker head.

In testimony of which invention, I have hereunto set my hand, at Philadelphia, on this 15th day of June, 1916.

HAROLD E. HOUSEMAN.
